UNITED STATES PATENT OFFICE

BENSON ORENSTINE, JOEL L. SCHLESINGER, AND HENRY REINSCHRIEBER, OF PHILADELPHIA, PENNSYLVANIA

DESIGN FOR A COMBINATION LAMP STAND AND BEVERAGE SET

Application filed June 17, 1932. Serial No. 44,121. Term of patent 3½ years.

To all whom it may concern:

Be it known that BENSON ORENSTINE, JOEL L. SCHLESINGER, and HENRY REINSCHRIEBER, citizens of the United States, residing at 2107 Fairmont Avenue, in the city and county of Philadelphia, State of Pennsylvania, have invented a new, original, and ornamental Design for a Combination Lamp Stand and Beverage Set, of which the following is a specification, reference being had to the accompanying drawing, forming part thereof.

Fig. 1 shows a front elevation of a combination lamp stand and beverage set embodying our new design; and

Fig. 2 shows a side elevational view thereof.
We claim:

The ornamental design for a combination lamp stand and beverage set as shown and above described.

BENSON ORENSTINE.
JOEL L. SCHLESINGER.
HENRY REINSCHRIEBER.
